UNITED STATES PATENT OFFICE

FRED J. NICHOLS, OF DAYTON, OHIO, ASSIGNOR TO FOR-ETA NUT COMPANY, OF ST. LOUIS, MISSOURI, A CORPORATION OF MISSOURI

DESIGN FOR A GLASS DISPLAY CASE

Application filed June 23, 1930. Serial No. 36,136. Term of patent 7 years.

To all whom it may concern:

Be it known that I, FRED J. NICHOLS, a citizen of the United States, and a resident of the city of Dayton, county of Montgomery, State of Ohio, have invented a new, original, and ornamental Design for Glass Display Case, of which the following is a specification, reference being had to the accompanying drawing, forming part hereof, in which

the drawings show a perspective view of the article showing my new design.

I claim:

The ornamental design for a glass display case, as shown.

In testimony whereof I have signed my name to this specification this 20th day of June, 1930.

FRED J. NICHOLS.
